UNITED STATES PATENT OFFICE.

CHARLES H. CLARK, OF CRAFTON, PENNSYLVANIA, ASSIGNOR TO CLARK CAR COMPANY, OF PITTSBURGH, PENNSYLVANIA, A CORPORATION OF NEW JERSEY.

ТИЛТИНГ СІД-ДАМП САР.

1,182,644.

Specification of Letters Patent. Patented May 9, 1916.

Application filed July 30, 1913. Serial No. 781,987.

To all whom it may concern:

Be it known that I, CHARLES H. CLARK, a citizen of the United States, and resident of Crafton, in the county of Allegheny and State of Pennsylvania, have invented certain new and useful Improvements in Tilting Side-Dump Cars, of which the following is a specification.

The primary object of this invention is to provide simple and efficient manually-operated means for tilting a side-dump car, said mechanism being preferably embodied in a powerful gear reduction or winch which is mounted on and movable with the body, being geared to a fixed portion of the car frame for effecting the desired movement of the body.

A further object is to locate manually-operated body-tilting means at opposite ends of the body and operative from opposite ends of the car, with the mechanisms so connected that both are actuated when either is operated.

Another object is to provide hand-actuated latch mechanism of improved construction for holding the body erect or in non-tilting position.

In the accompanying drawings, Figure 1 is an end elevation of a dump car equipped with the improved mechanism, the body and its actuating mechanism being shown erect or in normal position in full lines and in dumping position in dotted lines. Fig. 2 is a vertical cross-section on line 2—2 of Fig. 4. Fig. 3 is a vertical cross-section of a portion of one end of the car taken on line 3—3 of Fig. 1. Fig. 4 is a side elevation of one end of a car equipped with the improved mechanism, and Fig. 5 is a top plan with parts thereof broken away.

Referring to the drawings, 2 designates the longitudinal center sills of the car underframe, and supported at each end of the latter is an upright transverse frame 3, of which 4 is the wall-forming diaphragm. The car body 5 is supported adjacent each end by a transverse bolster 6 with the central portion of the bolster enlarged downwardly and curved to form the toothed rocker 7 which meshes with and is adapted to roll on the transverse horizontal beam 8. The load-carrying portion of the body consists of the normally horizontal floor 9, fixed end walls 10, and downwardly and

outwardly opening longitudinal side walls or doors 11, one of the latter forming a downward and outward extension at the dumping side of the car when the body is inclined, as shown in dotted lines in Fig. 1. Duplicate body-holding latch mechanisms are preferably provided at each side of each rocker, as shown in Fig. 1. Extending longitudinally through the underframe at the outer sides of girders 2 are shafts 12 to which are secured the hook-like latch heads 13. Shafts 12 extend to opposite ends of the car, and secured thereto are the hand levers 14 which extend upwardly through platform 15. Coöoperating with each latch head 13 is an arm 16 pivoted at its upper end to bolster 6, the lower portion of the arm being slotted at 16' where it embraces pin 17 carried by the guide link 18, said link being pivoted to and depending from the underframe and adapted to direct pin 17 into and out of position for engaging latch head 13. Shafts 12 extend from end to end of the underframe, so that all of latch heads 13 at one side or the other may be released by operating the appropriate lever 14 at either end of the car. The latches at the unreleased side remain in holding position, preventing the body from tilting in the wrong direction, but without interfering with the dumping operations, arms 16 of the unreleased latch devices simply moving downwardly over the latch-held pins 17, as will be understood.

The mechanism for tilting the car body and for controlling it throughout its tilting movement will now be described. Secured to and projecting outwardly from the opposite end walls 10 of the body are the bearing-forming trunnions 30 and journaled on each of these trunnions is pinion 31, Figs. 1 and 3, which meshes with transverse horizontal rack 32 at the under side of the top chord of end frame 3. Force for tilting the body is transmitted thereto through the trunnions 30 located at the center of rocking. Journaled in the tilting body and extending therethrough from end to end beneath floor 9 is shaft 33, and interposed at each end of the car body between shaft 33 and pinion 31 is a train of reducing gearing, the ends of the train being mounted on trunnion 30 and shaft 33, the intermediate portion of the train being mounted on journal 34 projecting from the

end of the car body. Gear wheel 35 of the train mounted on trunnion 30 is secured to pinion 31 by hub 36. Secured to each end of shaft 33 is a hand wheel 37, whereby the body may be dumped from either end, the interposed trains of gearing constituting winches of such type that the operation may be readily performed manually. After the appropriate lever 14 is thrown to release the latches which hold that portion of the body which is to rise in the tilting movement, the body is free to respond to the tilting movement transmitted through one of hand wheels 37. With the mechanism arranged as described, the dumping mechanisms are so connected that they operate in unison, tilting movement communicated at one end of the body being directly transmitted to the other end.

In the present adaptation, as in that of my above mentioned patent, the center of gravity of the loaded body lowers during the tilting movement and facilitates the dumping operation. At the same time the center of gravity of the car body itself rises, so that when entirely empty the tendency of the body is to rock back to upright or horizontal position, thus automatically righting itself, and automatically relatching. Wood or other buffer or cushioning devices 53 may be arranged on the underframe for checking and limiting the tilting movement, being engaged by the body when fully tilted, as shown in Fig. 2.

Each of the side doors 11 is hinged at 55 beneath floor 9 and is adapted to swing downwardly and outwardly, forming a chute-like extension which discharges the lading away from the track. The opposite doors are connected by the floating bar 56 and links 57, as shown and described in Patent No. 1,007,538, October 31, 1911, said bar being movable in a double guide 58 having the opposite upstanding curved faces 59 which control or direct the movement of the bar through the medium of rollers 60 at opposite sides of the latter and engaging said curved faces. The doors are operated by the connecting mechanism as described in said patent, the door at the dumping side of the body automatically opening as that side lowers, and automatically closing as the body returns to upright position. The connecting mechanism holds the doors closed when the body is in erect position, and similarly holds the inactive door during the dumping operation.

I claim:

1. In a dump car, the combination of an underframe, upright end frames, a body, rockers supporting the body on the underframe between the end frames and on which the body is adapted to tilt toward either side of the car, gearing carried by opposite ends of the body with an element of each of said

gearings rotatable about the axis of tilting of the body, and racks fixed to the end frames and with which said gearing elements, respectively, mesh.

2. In a dump car, the combination of an underframe, an upright end frame, a body, rockers supporting the body on the underframe and on which the body is adapted to tilt toward either side of the car, body tilting gearing mounted on the end of the body at the inner side of the end frame, a rack fixed to the end frame and with which said gearing meshes, a shaft extending from the gearing to the outer side of the end frame, and an operating wheel at the outer side of the end frame and secured to said shaft.

3. In a dump car, the combination of a frame, a body mounted to tilt thereon about a horizontal axis, said axis being movable horizontally as the body tilts, body-tilting gearing mounted on and movable with the body and with an element of said gearing rotatable about said axis of tilting, and a horizontal rack fixed to the frame and with which said gearing element meshes.

4. In a dump car, the combination of an underframe, an upright end frame, a body, rockers supporting the body on the underframe and adapted to tilt the body toward either side of the car, gearing mounted on and movable with the body, and a rack fixed to the end frame and with which said gearing meshes.

5. In a dump car, the combination of an underframe, upright end frames, a body, rockers supporting the body on the underframe between the end frames and adapted to tilt the body toward either side of the car, a body-tilting gearing located at each end of the body, and racks fixed to the end frames and with which the said gearings, respectively, mesh.

6. In a dump car, the combination of an underframe, upright end frames, a body, rockers supporting the body on the underframe between the end frames and adapted to tilt the body toward either side of the car, a shaft extending from end to end of the body, shaft actuating means, gearing carried by opposite ends of the body and operatively connected to said shaft with an element of the gearing at each end rotatable about the axis of tilting of the body, and horizontal racks fixed to the end frames and with which said gearing elements mesh.

7. In a dump car, the combination of an underframe, an upright open end frame, a body, rockers supporting the body on the underframe and adapted to tilt the body toward either side of the car, body-tilting gearing mounted on the end of the body at the inner side of the end frame, a shaft extending from the gearing through the end frame and an operating wheel on said shaft at the outer side of the end frame, and a

rack fixed to the end frame and with which said gearing meshes.

8. In a dump car, the combination of a tilting car body, an upright fixed frame, a rack mounted on the frame, gearing mounted on the car body and meshing with said rack, and a gearing - rotating hand - wheel mounted on and movable with the body and projecting therefrom beneath the rack - carrying portion of the upright frame.

9. In a dump car, the combination of fixed upright end frames, a tilting car body mounted between the frames, a rack carried

by each of said frames, gearing mounted on the body at each end thereof and meshing with the racks, a gearing operating shaft mounted on the body and extending from end to end thereof and movable therewith, and a hand-wheel at each end of the shaft.

In testimony whereof I affix my signature 20 in presence of two witnesses.

CHARLES H. CLARK.
